UNITED STATES PATENT OFFICE

WERNER B. HEIDELOFF, OF PLAINFIELD, NEW JERSEY, ASSIGNOR TO KENNEY SPECIALTY CO., OF NEW YORK, N. Y.

DESIGN FOR A DRINKING FOUNTAIN

Application filed November 19, 1932. Serial No. 46,080. Term of patent 3½ years.

To all whom it may concern:

Be it known that I, WERNER B. HEIDELOFF, a citizen of the United States, residing at 46 Westervelt Avenue, Plainfield, in the county of Union and State of New Jersey, have invented a new, original, and ornamental Design for a Drinking Fountain, of which the following is a specification, reference being had to the accompanying drawing, forming part thereof.

I claim:

The ornamental design for a drinking fountain as shown.

WERNER B. HEIDELOFF.
